REPLACEABLE HEELS FOR SHOES

Frank Cesta, 795 S. 8th St., Vineland, N.J.

Filed Nov. 13, 1959, Ser. No. 852,692

9 Claims. (Cl. 36—36)

This invention relates to detachable and replaceable heels for shoes.

It has heretofore been proposed to provide detachable heels for replacement when excessive wear occurred but the structures as heretofore proposed have been unduly complicated so as to be costly to manufacture, did not retain the heel tread members in firm fixed position in use, or have had other defects.

It is the principal object of the present invention to provide a replaceable heel having a minimum number of component parts and in which the component parts are simple in construction yet effective for their purposes.

It is a further object of the present invention to provide a replaceable heel construction in which the structure for releasing the heel tread member is readily accessible but does not detract from the appearance of the heel construction nor provide a location for the collection of dirt.

It is a further object of the present invention to provide a heel construction in which the walking pressure on the heel tread member tends to make the heel tread member tighter.

It is the further object of the present invention to provide a construction having a replaceable heel tread member and an improved connecting retaining mechanism between the heel tread member and the portion of the heel secured to the sole of the shoe.

Other objects and advantageous features of the invention will be apparent from the description and claims.

The nature and characteristic features of the invention will be more readily understood from the following description, taken in connection with the accompanying drawings forming part thereof, in which:

Figure 1 is a top plan view of the heel base portion of a shoe removed from the shoe and having the heel tread member attached thereto, parts being broken away to show the details of construction;

Fig. 2 is an underneath plan view of the heel base portion of the shoe, the heel tread member being detached therefrom;

Fig. 3 is a top plan view of the heel tread member removed from the shoe;

Fig. 4 is a vertical sectional view, enlarged, taken approximately on the line 4—4 of Fig. 1;

Fig. 5 is a vertical sectional view, enlarged, taken approximately on the line 5—5 of Fig. 1;

Fig. 6 is a fragmentary sectional view, enlarged, taken approximately on the line 6—6 of Fig. 1; and

Fig. 7 is a side elevational view illustrating the mounting of the heel tread member.

It should, of course, be understood that the description and drawings herein are illustrative merely, and that various modifications and changes can be made in the structure disclosed without departing from the spirit of the invention.

Like numerals refer to like parts throughout the several views.

Referring now more particularly to the drawings, for

2

purposes of illustration the base portion of a heel is illustrated at 10, the same being normally made of leather and permanently attached to the sole of a shoe S in any desired manner.

5 In accordance with the present invention, the heel base portion 10 is provided with a central opening 11 and has a recess 12 on the lower face 13 thereof for the reception of a locking plate 15. The locking plate 15 is preferably made as a metal stamping, and secured in position in any 10 desired manner such as by a plurality of screws 16 which extend upwardly into the heel base portion 10. The plate 15 has a side extension 17 which terminates at the outer face 18 of the heel base portion 10. The plate 15 has an opening 19 therethrough with a rear marginal edge 20 15 which serves as a hinge component or fulcrum; as herein-after explained.

The plate 15 is preferably provided with a struck up pivot tongue 21 contiguous to one side margin of the opening 11 for the reception and retention of the coiled 20 portion of a spring 22. The spring 22 has one end 23 thereof engaged with a holding tongue 24 also struck upwardly from the plate 15. The spring 22 has a resilient leg portion 25 extending substantially transversely across an opening 26 in the plate 15, a struck up tongue 27 25 being provided for limiting the movement of the spring leg portion 25 upon the release thereof.

In order to move the spring leg portion 25 to the desired position to permit of locking, an actuator pin 30 is provided, the inner end 31 of which is adapted to engage the spring leg portion 25.

The pin 30 is guided in part by a struck up tongue 28 extending upwardly from the plate 15 and having an opening 28a therethrough and by its disposition in a groove 29 in the heel base portion 10, the pin 30 being retained in the groove 29 by extension 17.

The pin has, intermediate its ends, an offset portion 32 which serves to limit the outward movement of the pin 30 when in an inward position and thereby to prevent the projection thereof beyond the face 18 of the heel base 40 portion 10 and by turning of the same for engagement in a recess 33 in the heel base portion 10 to permit locking of the spring leg portion 25 in an open or disengaged position.

The pin 30 preferably has a slot 34 in the actuator end 45 thereof for the insertion of a tool (not shown) to press the same inwardly and turn the pin 30 for engagement of the offset portion 32.

A heel tread member 35 is provided which may be made of any desired material but is preferably made of rubber of the desired shape and has a body portion with a plate 36, preferably of sheet metal and formed as a stamping molded or otherwise secured therein. The plate 36 has a pair of spaced hinge projections 37 which are adapted to engage over the rear marginal edge 20 of the plate opening 19 to provide a rear hinge.

The plate 36 at the opposite or forward end is provided with a ledge 38 extending therefrom. The ledge 38 has a slot 39 formed therein with an opening 40 and an upper margin 41 downwardly inclined to provide a wedging action upon engagement by the spring leg portion 25.

60 The mode of attachment and detachment of the heel pad 35 will now be pointed out.

When it is desired to initially apply a heel tread member 35 the pin 30 is pressed inwardly with a suitable tool 65 (not shown) engaging in the slot 34 thereof, the offset portion 32 being engaged at the recess 33 to hold the spring leg portion 25 away from the stop or limit tongue 27. The heel tread member 35 to be mounted is then brought to a position to engage the hinge projections 37 over the rear marginal edge 20 of the plate opening 19 and the ledge 38 is then moved upwardly through the opening 26, the slot opening 40 permitting the ledge 38

to be moved upwardly. The pin 30 is then turned and released to permit the spring leg portion 25 to move below the upper downwardly inclined margin 41 to lock and hold the heel tread member 35 in place.

It will be noted that the inclination of the upper margin 41 provides a wedging action which enhances the locking of the heel tread member 35 in position. The heel tread member 35 will thus be retained in tight fixed relation with respect to the heel base portion 10.

If replacement of the heel tread member 35 is required by reason of wear, a tool, as previously pointed out, is inserted in the slot 34 of the pin 30. The pin 30 is pressed inwardly to disengage the spring leg portion 25 from the margin 41. Upon turning of the pin to engage the offset portion 32 at the recess 33, the heel tread member 35 may be swung downwardly about the pivotal axis provided by the engagement of the hinge projections 37 with the edge 20 of the plate opening 19.

A new heel tread member 35 may then be inserted as previously explained and the pin 30 released so that the pin leg portion 25 can move to its locking position in the slot 39.

I claim:

1. A heel construction comprising a heel base portion and a heel tread portion with interior facing parts, one of said portions having a plate secured on its facing part, said plate having spaced openings therethrough at opposite ends thereof, said plate having a spring mounted thereon on a side face thereof opposite its facing part, said spring having a leg extending over said side face and in intersecting relation to one of said openings, the other of said portions having members projecting therefrom for pivotal engagement with marginal portions of one of said openings in said plate and a ledge spaced from said members projecting therefrom and insertable through the other of said openings in said plate, said ledge having a transverse slot for locking engagement by said spring leg.

2. A heel construction as defined in claim 1 in which a control pin is provided in one of said portions for releasing engagement with said spring leg.

3. A heel construction as defined in claim 1 in which a control pin is provided in one of said portions for releasing engagement with said spring leg and said pin has an offset part for holding said leg in unlocked position.

4. A heel construction as defined in claim 1 in which said plate has a struck up tongue on which said spring is pivotally mounted and said plate has a tongue limiting the movement of said spring leg in one direction.

5. A heel construction comprising a heel base portion and a heel tread portion with interior facing parts, said heel base portion having a plate secured on its facing part, said plate having spaced openings therethrough at opposite ends thereof, said plate having a spring mounted thereon on a side face thereof opposite its facing part, said spring having a leg extending over said side face and in intersecting relation to one of said openings, said heel tread portion having members projecting therefrom for pivotal engagement with marginal portions of one of said openings in said plate and a ledge spaced from said members projecting therefrom and insertable through the other of said openings in said plate and said ledge having a transverse slot for locking engagement by said spring leg.

6. A heel construction as defined in claim 5 in which a control pin is provided in said heel base portion for releasing engagement with said spring leg.

7. A heel construction as defined in claim 5 in which a control pin is provided in said heel base portion for releasing engagement with said spring leg, and said pin has an offset part for holding said leg in unlocked position.

8. A heel construction as defined in claim 5 in which said plate has a struck up tongue on which said spring is pivotally mounted.

9. A heel construction as defined in claim 5 in which said plate has a struck up tongue on which said spring is pivotally mounted and said plate has a tongue limiting the movement of said spring leg in one direction.
